By

J. McJohn Attorney

UNITED STATES PATENT OFFICE.

GEORGE G. KUNZMANN, OF CEDAR RAPIDS, IOWA.

PUMP.

Application filed February 2, 1924. Serial No. 690,273.

To all whom it may concern:

Be it known that I, GEORGE G. KUNZMANN, a citizen of the United States, residing at Cedar Rapids, in the county of Linn 5 and State of Iowa, have invented certain new and useful Improvements in Pumps, of which the following is a specification.

This invention relates to pumps, and the object of the invention is to provide means 10 for attaching the fulcrum-bearing cap to the barrel or body of the pump so that it will remain rigidly and permanently in place, the connection or disconnection of the parts being easily and conveniently effected.

15 In the manufacture of iron pumps it has been the common practice to secure the cap which carries the pump-handle fulcrum, to the body of the pump by one or more set-screws through a flange of the pump-cap. 20 The tendency of such set-screws is to continually loosen under the vibration and strain due to pumping, and in an effort to screw the set-screws tightly enough to hold, a great many pumps have been broken. A 25 remedy for this fault was found in flanging the pump and cap, or providing lateral, bolt-holding lugs, and clamping the parts together by means of bolts parallel with the pump-body. The result was a perfectly 30 strong and durable pump-cap attachment—which the dealers would not buy. To hold the pump-cap and handle with one hand, and try to insert the bolts with the other, and start the nuts on the bolts at the same 35 time, was such an annoying performance that in ordering new caps for repairs, or new pumps, the dealers would still specify the old set-screw type. The improvement which is the subject matter of this invention 40 makes it possible for one to assemble the parts very easily, supporting the cap with one hand, and with the other slipping in the fastening bolts successively as the cap is turned, until all are inserted, then putting 45 on the nuts and screwing them down until the whole structure is as rigid as though made in one piece.

The device is fully described and claimed in the following specifications, reference being had to the accompanying drawing, in which:—

Fig. 1 is a side elevation of the upper part of a pump, showing the improved device. Fig. 2 is a central, vertical section of the

same, in the line 2—2 of Fig. 5. Fig. 3 is 55 an elevation of the upper end of the pump-barrel, showing the disposition of annular flanges and the recess for the insertion of fastening bolts. Fig. 4 is a plan view of the same. Fig. 5 is a plan view of the pump- 60 cap, as seen from below.

In the drawing, the numeral 5 denotes a pump-barrel or standard, through which the pump-rod 6 passes to the valve and cylinder, not shown, and hereafter designated as the standard. To the upper end of this is attached the cap 7, which carries an upstanding fulcrum 8, to which is pivoted the hand-lever 9.

Referring to Figs. 2 and 3, more particularly, it will be seen that the standard near the upper end is provided with an annular groove 10, and below this is expanded in an annular flange 11. A gap 12 in this flange permits the insertion from below of the 75 hook-bolts 13 for holding the cap in position. The latter is socketed at 14 to fit over the top of the standard, and rest on the flange. At suitable intervals, preferably three, the body of the cap is expanded at 15 80 to form seats for said bolts. The hooked head portions of the bolts are made rectangular, and the seats, as shown in Fig. 5, are adapted to prevent the bolts from turning. In Fig. 2 it will be seen that the hook of 85 the bolt engages the groove in the standard, while the flange of the standard at the same time supports the bolt, whose threaded upper end passes through a hole 16 at the top 90 of the cap. With the bolts in position, and the nuts screwed tightly, it is evident that the fulcrum-cap may be so rigidly secured as to become and remain a stable part of the 95 pump.

In assembling the parts the cap is set in 95 position on the standard. With one hand the operator then turns it so that one of the bolt-seats will register with the recess in the flange. A bolt is then slipped in, and the cap turned to position for the next bolt, 100 and so on successively until all the bolts are in place. A single nut started on a bolt will now hold the parts together, and the other nuts may be put on and tightened at convenience. In the operation none of the bolts 105 can fall out until all are in place. To remove the cap, the nuts are taken off all the bolts, and then by merely turning the cap

the bolts will drop out as they reach the gap in the flange.

Having thus described my invention, I claim:

1. The combination of a pump-cap having a plurality of hook-bolts disposed therein, and a pump-standard fitting inside said cap, and grooved to receive the hooks of said bolts, and provided with a bolt-supporting flange with a single gap to admit a bolt.

2. Combined with a pump standard shouldered at the upper end to engage with hook-bolts, and with a lower disposed flange to support the bolts, with a single gap in said flange, a pump-cap fitting over said shouldered end, and provided with laterally disposed seats to receive a plurality of hook-

bolts one by one, as the cap is turned to bring the seats in register with said gap.

3. Combined with a pump-cap having a plurality of laterally disposed hook-bolts seated therein, a pump standard having a grooved neck to receive the hooks of said bolts, and a flange below the groove to support the bolts in their seats, said flange being continuous except for a single gap, through which the bolts are successively inserted in their seats.

In testimony whereof I affix my signature in presence of two witnesses.

GEORGE G. KUNZMANN.
